(57) **CLAIM**

The ornamental design for a vehicle front deflector, as shown and described.

DESCRIPTION

FIG. 1 is a front and left perspective view of a vehicle front deflector showing our new design;

FIG. 2 is a front elevation of the vehicle front deflector of FIG. 1;

FIG. 3 is a left elevation view thereof;

FIG. 4 is a right elevation view thereof;

FIG. 5 is a rear elevation view thereof;

FIG. 6 is a bottom view thereof; and,

FIG. 7 is a top view thereof.

The broken lines in the drawings depict portions of the vehicle front deflector that form no part of the claimed design.
